UNITED STATES PATENT OFFICE

137,979

DESIGN FOR A HYDROPLANE

Antoine Gazda, Providence, R. I.

Application April 17, 1943, Serial No. 109,987

Term of patent 14 years

(Cl. D71—1)

To all whom it may concern:

Be it known that I, Antoine Gazda, a citizen of no country, residing at Providence, Rhode Island, have invented a new, original, and ornamental Design for Hydroplanes, of which the following is a specification, reference being had to the accompanying drawing, forming a part thereof.

Fig. 1 is a side elevational view of a hydroplane showing my new design, and

Fig. 2 is a top plan view of the hydroplane shown in Fig. 1.

I claim:

The ornamental design for a hydroplane, as shown.

ANTOINE GAZDA.
